Application May 11, 1949, Serial No. 2,568

Term of patent 14 years

(Cl. D74—1)

To all whom it may concern:

Be it known that we, Richard S. Krause and Garfield L. Beckstrom, citizens of the United States, residing at Chicago, in the county of Cook and State of Illinois, have invented a new, original, and ornamental Design for a Combined Letter Opener and Magnifying Lens, of which the following is a specification, reference being had to the accompanying drawing, forming a part thereof.

In the drawing:

Figure 1 is an edge elevational view of a combined letter opener and magnifying lens showing our new design, the lens being shown in extended position;

Fig. 2 is an edge elevational view thereof with the lens retracted;

Fig. 3 is a side elevational view thereof with the lens in extended position;

Fig. 4 is a side elevational view thereof with the lens retracted;

Fig. 5 is an end elevational view of the magnifying lens end thereof; and

Fig. 6 is an end elevational view of the opener end thereof.

The side not shown is substantially the same as the one shown.

We claim:

The ornamental design for a combined letter opener and magnifying lens, substantially as shown and described.

RICHARD S. KRAUSE,
GARFIELD L. BECKSTROM.
